UNITED STATES PATENT OFFICE.

WILLIAM McLAUGHLIN, OF LOS ANGELES, CALIFORNIA.

BEVERAGE COOLER AND DISPENSER.

Application filed February 19, 1925. Serial No. 10,308.

To all whom it may concern:

Be it known that I, WILLIAM McLAUGHLIN, a citizen of the United States, residing at Los Angeles, in the county of Los Angeles and State of California, have invented new and useful Improvements in Beverage Coolers and Dispensers, of which the following is a specification.

This invention relates to beverage coolers and dispensers.

An object of the invention is to provide in a beverage cooler and dispenser an ice container adapted to retain the ice or cooling element within and separated from the beverage being dispensed and to provide this ice container with exterior baffle plates and fins for the purpose of agitating and stirring the beverage in order to keep the ingredients thoroughly mixed and to disturb any collection of sediment on the bottom of the dispenser.

It is an object of the invention to accomplish the foregoing results without removing the cover from the dispenser, thus doing away with an unsanitary practice which often permitted foreign matter to enter a dispenser when the cover was removed and a stick or spoon used for stirring.

A further object is to provide a cooler and an ice container both made of glass so that in dispensing beverages the salesman and the customer may both see the liquid being dispensed and the ice in the container, and that the ice is separate from the liquid.

Other objects and advantages will be made manifest in the following specification of an embodiment of the invention illustrated in the accompanying drawings, in which:

Figure 1 is a vertical sectional view of the beverage cooler and dispenser.

Figure 2 is a horizontal sectional view of the ice container employed and the baffle plates and fins, taken on the line 2-2 of Figure 1.

Figure 3 is a fragmentary sectional view of an ice container having a modified form of baffle plates and fins.

The details of construction and use of the invention are as follows:

An ordinary type of cylindrical container such as a jar 1 rests upon a conventional base 2 and is provided with a dome shaped cover 3 which is adapted to seat upon the upper rim of the glass jar 1 and a short annular sleeve 4 effects a dust proof fit with

the upper end of the glass jar. A faucet 5 is mounted at the lower end of the jar for the purpose of dispensing the beverage contained in the dispenser as indicated at 6.

The ice container or cooling element consists of a cylindrical container 10 such as a glass jar, which is smaller in diameter and slightly less in height than the glass jar 1. Ice is represented by 11, it being well known that ice when retained out of actual contact with liquid will last much longer without melting and at the same time produce a cooling effect for the liquid surrounding the ice container. The mouth of the ice container 10 is formed with a bead 12. Immediately below the bead 12 is a collar 13 made preferably of wire material and formed of a single piece looped at one side of the container as shown at 14 and the free end twisted upwardly and bent to provide a hook 15 on the side of the container opposite the loop 14. A link 16 is formed with an eye 17 at one end which is adapted to insertion in the loop 14 and the body of the link 16 extends horizontally above the mouth of the ice container 10 and is adapted to be engaged against its own spring resistance by the hook 15. A rod 20 having a hole 21 at its lower end adapted to receive the link 16 is threaded at its upper end and projects through a small opening 21 in the cover 3. A knob 22 provided with internal threads is screwed to the upper end of the rod 20. The length of the rod is so proportioned that when the knob 22 carrying the rod 20 is resting upon the cover 3 the ice container 10 will be suspended a short distance from the bottom of the glass jar 1 for a purpose hereinafter described.

A particularly novel feature of the beverage cooler and dispenser consists of one or any desired number of baffle plates 23 surrounding the ice container 10 and adapted to extend radially therefrom. These baffle plates are preferably formed of glass and made integrally with the ice container 10 as illustrated in Figure 2. However, a modified form of baffle plate may consist of a metal strap 35 having a U shaped cross section and a small opening 36 at one end of the strap through which a tongue 37 on the other end of the strap is adapted to be drawn and folded back as at 38 to secure the strap in place.

The lowermost baffle plates indicated at 28, are also preferably formed of glass in-

tegrally with the ice container 10, and consist in addition to the horizontal baffle plates 28 of downwardly extending fins 31 and 32 diametrically crossing each other. 5 Or, the lowermost baffle plates may be formed of a metal strap having a U shaped cross section similar to strap 35 and the baffle plate 39 formed with a downwardly extending cylindrical wall provided with a 10 bottom plate 40, thus affording a cup-like portion 41 adapted to snugly enclose the bottom of the ice container 10. Extending downwardly from the bottom plate 40 is a diametrically disposed fin 42. A second 15 fin 43 extending transversely of the fin 42 is also projected downwardly from the plate 40. The fins 31 and 32 or 42 and 43 reach substantially to the bottom of the glass jar 1.

20 In the use of the invention, if sediment has collected at the bottom of the glass jar 1, or if it is desired to agitate or stir the beverage 6 for other reasons, the operator will grasp the knob 22 and may severely 25 agitate the beverage by an up and down reciprocating motion such as is employed in churning. The baffle plates 23 will engage the liquid in a more effective manner than would an ordinary spoon inserted from 30 the top. The ice container 10 may then be rotated by turning the knob 22, the motion being imparted through the rod 20, the link 16 and the collar 13 which snugly fits the ice container 10. The resulting rotation will cause the fins 31 and 32 to stir the 35 liquid element or sediment at the bottom of the glass jar 1 and thus aid in thoroughly mixing the contents of the dispenser. It will be noted that this stirring and agitating 40 operation may be carried on without removing the cover 3, thus preventing dust from entering the beverage cooler and dispenser and further preventing the cooling properties from escaping.

45 Obviously if it is desired to remove any of the parts for cleaning or other purposes the cover 3 may be slipped off of the glass jar 1, the link 16 unhooked from the hook 15 and the rod 20 slipped off of the link 16.

50 The baffle plates 23 and 28 and the fins 31 and 32 may be made in various sizes or shapes integrally with an internal cooling element of any dispensing device.

55 By utilizing a glass jar and a glass ice container, a person may readily see how much ice is in the container and as the

beverage is being dispensed the purchaser will have visible evidence that it is not being diluted with ice water. Moreover, many people have a prejudice against drinking 60 water from water jars in that the water is frequently contaminated by the ice and with the visible ice container with the ice showing therein a person has visible evidence that the ice does not contaminate the drinking 65 water.

Various changes may be made without departing from the spirit of the invention as claimed.

What is claimed is:

1. A beverage cooler comprising in combination a glass jar having integral walls and base and a faucet therefor, an ice container formed of glass having integral walls and base and an open top with a bead thereabouts, a wire collar secured to the ice container below the bead, a loop formed on one side and having a hook formed on the other side of the collar, a link having an eye connected to the loop and its other end engaging the hook, a cover fitted on the container and having an aperture through the top, a rod fitting through said aperture and having a knob at the upper end and an opening in its lower end, said opening having the said link pass therethrough, whereby the ice container may be moved without disturbing the cover.

2. An ice cooler comprising in combination a jar having an open mouth to contain a beverage, a substantially cylindrical ice container insertable through the open mouth of the jar, a plate secured to the lower end of the ice container and having a series of lateral flanges and a fin at the bottom, a cover for the jar and means extending through the cover connected to the ice container to reciprocate and rotate the container and means to withdraw the beverage from the jar.

3. An ice cooler as claimed in claim 2, having in addition a baffle comprising a strap having a U-shaped cross section adapted to encircle the ice container, one end of the strap being provided with an opening and the other end being extended to form a tongue, said tongue being adapted to engage through the opening and clamp the baffle.

In testimony whereof I have signed my name to this specification.

WILLIAM McLAUGHLIN.
